BUILDING STONE

Filed March 18, 1927

UNITED STATES PATENT OFFICE.

BERNARDO FERNANDEZ DE LAS HERAS, OF MADRID, SPAIN.

BUILDING STONE.

Application filed March 18, 1927. Serial No. 176,524.

This invention relates to building stones for the erection of buildings either above or below the surface of the earth, and particularly artificial stones, such as are made of a mixture of slag, cinders, sand, lime, and cement.

According to the invention the stones are made of such a size as to be capable of taking supports for a suspension scaffolding and taking channels for flues, water mains and the like; and for this purpose the stones are provided with horizontal perforations running through the wall from the inside to the outside, so as to take the scaffolding supports, and in order to take the conduits, flues or the like, the stones are provided with channels running vertically in the thickness of the wall, which vertical channels have no connection with the horizontal transverse channels. This system is especially suited for the erection of high buildings (such as sky-scrappers) and also of high chimneys (such as factory chimneys).

The provision in stones of walls of small channels running horizontally along the wall, so as to afford circulation of the air along the latter, is already known; as is also the connection of such channels with small air-channels running vertically in the wall, or the provision at the corners of walls of stones with channels leading through from above to below, into which the various air-channels running along the wall enter. These channels are again connected with the air outside by other cross-channels.

Arrangements of that kind serve hygienic purposes, but can not do justice to the practical requirements aiming at the rapid and cheap erection of buildings, walls or the like. Such practical requirements are, however, satisfied by the arrangement shown in this invention, as with this invention it is not necessary to build special scaffolding in erecting a wall, nor is it necessary to construct chimney flues or other exhaust or drainage channels, as the arrangements therefor are provided in the stones themselves, whereby the manufacture of the stones is not rendered more expensive, whilst the erection of buildings or walls with such stones is considerably cheapened. In the removal of the stones, for example in raising or lifting them, bars can be placed through the openings provided for the scaffolding

supports, with the result that the transport of the stones is greatly facilitated.

In order to avoid the necessity of having to lay special pipes, for draining water or other liquids, in the openings running vertically with respect to the wall, these channels may with advantage be rendered waterproof and used directly as water or other conduits. In erecting a wall with stones of this kind the suspension scaffolding, which renders the building independent of the erection of high scaffolding, is made by placing the supports for the scaffolding through the channels running horizontally through the thickness of the wall from the inside to the outside and then joining at least two of these supports tightly together by means of vertical scaffolding props on either side of the wall, where-upon the scaffolding is completed in the usual way.

The drawing attached hereto shows the invention applied to a building in course of erection. The blocks or stones are designated by M, M; P and R are archstones and S are blocks for filling-in between the girders. The letters m and n represent the cylindrical cavities of the blocks.

The figures 1, 2, 3, 4, 5, 6, 7, 8 and 9 are the horizontal bars, which are introduced into the blocks. I, II, III, IV and V are vertical scaffolding props, to which the bars are fastened. X, Y and Z represent the flooring boards of the scaffolding.

To erect a wall, the blocks M are placed side by side so that the vertical ends of the stones of the first row do not coincide with those of the next row, and at the same time so that in each case two horizontal holes m and n coincide on either side. The blocks of one row form a layer of the wall. Into the holes 1, 2, 3, etc. are placed the scaffolding bars, the ends of which, as may be seen from the drawing, project externally.

These bars are in each case placed so that they form a vertical line with the bars of the lower layer of the wall and can be fastened to the scaffolding ties I, II and III, thus preventing any slipping of the latter to either side. Protective boards are also fitted to the scaffolding ties in the usual manner. The flooring boards are laid on the bars, so that a complete suspension scaffolding is obtained.

As a further precaution, the scaffolding

ties are fastened on the outside with screws. Upon completion of a layer of the wall, the lower bars are taken out and laid into the next layer above and fastened in the manner 5 above described.

As the blocks are laid one upon another in the manner stated, a chimney is formed in the thickness of the wall, which may be used either as a flue or for laying electrical or gas 10 mains. In addition, provided the walls are rendered waterproof, water can be flushed through the channel thus formed.

Having now described my invention, what I claim is:

- 15 1. The herein-described method of building a wall or the like, consisting in applying superimposed courses of building units with certain of such units formed with transverse openings, removably inserting scaffold-supporting elements in such transverse openings 20 with the elements projecting beyond the face

of the wall and held in such transverse openings at substantially right angles to the face of the wall, and utilizing the projecting portions of such elements as scaffold supports. 25

2. The herein-described method of building a wall or the like, consisting in applying superimposed courses of building units with certain of such units formed with transverse openings, removably inserting scaffold-supporting elements in selected transverse openings in each of two vertically spaced courses of units, the elements projecting beyond the face of the wall and being held in the openings at substantially right angles to such 30 wall face, connecting the outer ends of the elements together for bracing, and utilizing the elements beyond the face of the wall as scaffold supports. 35

In testimony whereof I affix my signature.

BERNARDO FERNANDEZ de las HERAS.
